UNITED STATES PATENT OFFICE.

RALPH W. CARNAHAN, OF CLEVELAND, OHIO, ASSIGNOR, BY MESNE ASSIGNMENTS, TO THE PARAMOUNT FIRE ALARM ENGINEERING COMPANY, OF CLEVELAND, OHIO, A CORPORATION OF OHIO.

SIGNAL BOX.

Application filed November 20, 1922. Serial No. 602,113.

This invention relates to signal boxes, such as are used for fire alarms or the like, for transmitting electric signals by intermittently making and breaking an electric circuit at 5 predetermined intervals.

The objects of the invention are to provide a signal box of this character in which the signal transmitting mechanism is operated by means of a weight connected to a 10 chain of gearing which operates the make and break device, the weight being arranged to be raised to put the gearing into operation, when it is desired to turn in an alarm.

A further object of the improvement is the 15 provision of means for giving four complete transmissions of the signal or box number with one complete operation of the mechanism, an operating lever being provided for raising the weight, the device being so constructed that a slight movement of the operating lever will give at least one complete transmission of the box number; means being also provided for permitting free movement of the lever, after the same has been operated to 20 start the mechanism, without interference with the operation of the signal mechanism.

A still further object is to provide a make and break device operated by the signal wheel, the contacts being arranged to operate 25 to make and break the circuit within mercury cups, the movable contact points being immersed in the mercury when the circuit is closed, preventing corrosion of the contact points; the movable contacts being provided 30 with open tips to prevent the forming of an arc when they are raised out of the mercury to break the circuit.

Another object of the invention is to provide a locking means for retaining the usual 40 glass panel in position in the door of the signal box and arranged to permit the glass to be easily and readily replaced, after the box has been operated.

Other objects of the invention are to provide 45 signal boxes of the character mentioned in which complicated adjustments are eliminated, thus doing away with causes of failure to operate and to register accurately and permitting of their being manufactured economically, thus providing a signal box which is efficient and durable in operation and construction.

The above and other objects may be attained by constructing the signal box in the manner illustrated in the accompanying 55 drawings, in which—

Figure 1 is an elevation of a signal box embodying the invention, showing the door thereof opened;

Fig. 2, a plan view of the signal transmitting mechanism removed from the box;

Fig. 3, a section on the line 3—3, Fig. 2;

Fig. 4, a section on the line 4—4, Fig. 2;

Fig. 5, a section on the line 5—5, Fig. 2;

Fig. 6, an enlarged elevation of the signal 65 transmitting mechanism showing the make and break device in section;

Fig. 7, a section on the line 7—7, Fig. 6;

Fig. 8, an elevation of the yoke which carries the movable contacts in the make and 70 break device;

Fig. 9, an enlarged elevation of one of the movable contact points;

Fig. 10, a section on the line 10—10, Fig. 1;

Fig. 11, a section on the line 11—11, Fig. 10; 75

Fig. 12, a section on the line 12—12, Fig. 10; and

Fig. 13, a detached elevation of the sliding rack bar which engages the train of gearing.

Similar numerals of reference indicate corresponding parts throughout the drawings.

The signal mechanism is contained within the usual box 1, provided with the hinged door 2 having the compartment 3 formed therein and provided with the opening 4 through which the handle portion of the operating lever 5 extends, a glass panel 6 covering the compartment, thereby making it necessary to break the glass in order to have access to the operating lever, as the door is 80 normally held in the closed position by means of the lock 7.

A pair of notched lugs 8 (see Figs. 10 and 11) are provided upon the outer face of the door near opposite lower corners of the compartment 3 and are arranged to receive the lower edge of the glass panel 6, the upper edge of said panel being received in the groove 9 formed in the rib 10.

For the purpose of locking the glass panel 100 in place over the compartment 3, a pair of rotatable bolts 11 are journaled in the door and in the bearing block 12, and provided with the notched ends 13 extending into the

groove 9. A rocker arm 14 is fixed upon each of the bolts 11 and said arms being connected together by the link 15 having the upturned end 16 which serves as a handle for operating 5 the same.

In replacing the glass panel in the door, the bolts 11 are rotated by means of the link 15, until the cut-out portion 13 of each bolt is moved into position to permit the glass panel 10 to be moved upward out of engagement with the notched lugs 8, when the lower end of the panel may be pulled outward and the broken panel removed.

Leaving the bolts in this position, the 15 upper end of a new panel may be inserted into the groove 9, the panel being raised until the lower end is passed over the lugs 8 and may be dropped into the notches thereof. The bolts 11 are then rocked back into the 20 position best shown in Fig. 12, preventing the panel from being moved upward and locking the same securely in place.

As the bolts 11 are located upon the inner 25 side of the door and the cut-out ends thereof are protected by the rib 10, it will be seen that after the glass panel is placed in position, and the door closed and locked, the panel cannot be removed from the outside of the box, and it is necessary to break the glass in order to 30 have access to the handle of the operating lever 5.

A signal transmitting mechanism is mounted upon a frame comprising the front and rear plates 17 and 18 respectively, connected together at their corners as by the 35 posts 19 and supported upon the rear wall of the box as by the brackets 20.

The operating lever 5 (see Figs. 6 and 7) is pivoted at 21 between a pair of bracket 40 plates 22 mounted upon the front plate 17, and extends through a slot 23 in said front plate, being provided at its rear end with the gear segment 24 which meshes with the sliding rack bar 25 slidably mounted in the 45 guide-ways 26, and provided with a pawl 27 pivoted intermediate its extremities as at 28, and arranged to be normally held in the position shown in Fig. 7, by means of the pin 29 extending through the guide-ways and 50 engaging the lower end of the pawl to throw the same into this position.

A rack bar 30 (see also Fig. 3) is slidably mounted parallel to and in rear of the bar 25, being mounted for vertical reciprocation in 55 the guide-ways 31, a roller 32 engaging the upper end of said rack bar. A substantially triangular pawl 33 is pivoted at its upper end as at 34 in a slot 35 formed in the rack bar 30, the flat face 36 thereof being arranged to be engaged by the flat end 37 of the pawl 27.

A spring 38 engages the upper end portion 60 of the pawl 33 and is arranged to throw said pawl rearward into the groove 39, when the pawl is disengaged from the pawl 27, the

cam surface 40 at the lower end of the groove being arranged to normally move the pawl 33 into the position shown in Fig. 7, when the parts are in the initial position.

The rack bar 30 meshes with a gear wheel 70 41 fixed upon a shaft 42 which is journaled through the plates 17 and 18, the segment 43 (see Figs. 2, 3, 4 and 6) being also fixed upon said shaft and provided with the peripheral groove 44, a steel ribbon 45 being connected 75 at the upper end of said groove and supporting at its lower end the weight 45^a, which is slidably mounted upon the vertical guide rods 46, carried in the upper and lower brackets 47 and 48 respectively, which are 80 mounted upon the rear face of the box.

Studs 49 and 50 (see Fig. 4) limit the upper and lower movement of the segment 43. When the segment is in the normal position, as best shown in Figs. 1 and 6, the weight 85 45 will be spaced slightly above the lower bracket 48, thus suspending the weight from the sector at all times.

A ratchet wheel 51 (see Fig. 5) is placed upon the shaft 42 and the gear wheel 52 is 90 journaled upon said shaft adjacent to the ratchet wheel, and provided with a pawl 53 normally held in mesh with the ratchet teeth by means of the spring 54. The gear 52 meshes with a pinion 55 fixed upon the shaft 95 56. A gear 57 is fixed upon the shaft 56, and meshes with the pinion 58 fixed upon the shaft 59, a gear 60 mounted upon said shaft meshing with a pinion 61 upon the shaft 62.

A gear 63 is fixed upon the shaft 62 and 100 meshes with a pinion 64 upon the shaft 65, an escape wheel 66 being also fixed upon said shaft and engaged by the palette 67 which is pivoted as at 68. The palette acting upon the escape wheel, thus provides for a uniform 105 operation of the gearing when the same is operated by the downward movement of the weight.

The shaft 59 extends through the front 110 plate 17 and the signal wheel 69 is fixed upon the outer end thereof, the circumferential surface of said signal wheel being provided with groups of projecting teeth 70 arranged in any desired combination to produce the formation of the signal impulses, these teeth 115 being preferably of the shape best shown in Fig. 6, having a rear vertical edge and a downwardly and forwardly inclined forward edge.

The lever 71 is pivoted at 72 upon the front 120 face of the front plate 17, and is provided with the depending tooth 72^a which normally rests upon the periphery of the signal wheel 69, and is arranged to be engaged by the groups of teeth upon the signal wheel to intermittently raise and lower the lever at 125 predetermined times, as will be later described.

For the purpose of insulating the mechanism from the make and break device which 130

is operated through the lever 71, a knob 73 of hard rubber or the like is mounted upon the free end of the lever which contacts with the vertical rod 74 of the yoke 75, which carries the movable contacts 76 of the make and break device.

The rod 74 is slidably mounted through a suitable vertical bearing in the insulated housing 77 within which the make and break device is contained, and the arms 78 of the yoke slide within vertical passages in said housing, the movable contacts 76 upon said arms being located in the chambers 79 formed in said housing, cups 80 being threaded into the lower ends of said chambers and provided with the fixed contact points 81, to which the wires 82 are connected, said wires leading to suitable binding posts 83 to which wires 84 are attached, said last named wires leading to the fire station or other point where the signal is to be given, it being, of course, understood that a suitable source of electrical energy is located in the circuit.

Each of the cups 80 contains mercury and the movable contact members 76 are provided with the open tips 85 preferably formed of thin strips of suitable conducting material bent into the form shown in the drawings, and connected at their extremities to the cylindrical portions 76 of the movable contact members, thus leaving the central openings 86 through the tips through which the mercury may flow when the movable contact members are in the normal position, as illustrated in Fig. 6.

With this construction of make and break device, when the yoke is raised to move the movable contact points out of engagement with the contact points 81, a small portion of the mercury will be lifted by the open tips upon the movable contact members, preventing an arc from being formed between the contact members.

The lower end of the rack bar 30 is provided with the shoulder 87, terminating in the downwardly tapered portion 88, and this shoulder is arranged to engage the tail portion 89 of the lever 90 when the parts reach the lowermost or normal position. The lever 90 is pivoted near the tail portion as at 91 and provided at its other end with the hooked portion 92 arranged to be moved into the path of the stop pin 93 upon the gear 60, always stopping the mechanism in the same position as shown in Fig. 3. A pair of stop pins 94 mounted upon the front plate above and below the lever 90, limit the movement of said lever.

Attention is called to the free end portion 95 of the lever 71 which is provided with the finger button 96, providing a key by means of which the lever may be manually operated. This construction is especially desirable for signalling from a box which has been operated on account of fire in that particular

fire district, as the fire chief may manually operate the finger key to transmit any desired code signal to fire headquarters, during the progress of the fire, as for instance, it may be necessary to signal to fire headquarters to send other fire companies to the scene of the conflagration or with the use of this key, information regarding the progress of the fire or that the fire has been extinguished may be easily transmitted to headquarters, as any predetermined code of signals may be provided for transmitting such messages.

In operating the mechanism, it is first necessary to break the glass panel 6 in order that the handle of the operating lever 5 may be grasped. The operating lever is then pulled downward to the full extent of its movement and released. This movement of the operating lever through the gear segment 24 thereon, raises the rack bar 25, the pawl 27 thereof engaging the flat surface of the pawl 33 upon the rack bar 30, moving the rack bar 30 upward and rotating the gear 41 in a direction to move the segment 43, which is also fixed upon the shaft 42, upward, raising the weight 45 upon the guides 46.

As the shaft 42 is thus rotated in this direction, four of the teeth upon the ratchet 51, will in succession, click under the spring pressed pawl 53, upon the gear 52 which, being loosely mounted upon the shaft 42, is held against rotation with the shaft by engagement with the pinion 56.

As the operating lever reaches the limit of its downward movement, the pawl 33 will be engaged by the stop pin 99, throwing said pawl out of engagement with the pawl 27 and into the groove 39, the spring 38 holding the pawl 33 in this position.

The mechanism will immediately start to operate by the downward movement of the weight 45, which through the segment 43 and shaft 42, will move the ratchet 51 and through the pawl 53 upon the gear 52, the chain of gearing above described will be operated to rotate the signal wheel 69 in the direction of the arrow shown on Figs. 1 and 6.

Any further movement of the operating lever in either direction, will not affect the operation of the mechanism, as the rack bar 25, being disconnected from the rack bar 30, may be freely reciprocated without interference with the downward movement of the rack bar 30. With a complete downward movement of the operating lever, as above described, the pawl 53 will click over four of the teeth upon the ratchet 51 and four complete revolutions of the signal wheel 69 will be made before the mechanism is brought to a stop.

Should the operator of the device become excited, and only give the operating lever a partial movement, the pawl 53 will be caused to click over one, two or three of the ratchet teeth 51, thus producing one, two or three

complete revolutions of the signal wheel and transmitting the same number of signals to the fire station or other point where the recording mechanism is located.

5 As the signal wheel is thus rotated, the groups of teeth thereon engaging the tooth 72 upon the lever 71, will raise and lower said lever intermittently, in turn raising and lowering the yoke carrying the movable contact 10 points, thus making and breaking the circuit at predetermined intervals and producing the proper impulses at the fire station.

As the last revolution of the signal wheel is completed, the sliding rack bar will have 15 reached its lowermost position, the shoulder 87 thereof engaging the tail 89 of the lever 90, throwing the hook portion 92 of said lever upward into the path of the stop pin 93 upon the gear 60, while at the same time the 20 segment 43 will engage the stop pin 60, preventing further downward movement of the weight and always stopping the gear at the proper position, the signal wheel 69 being brought to a stop in the position shown in 25 Figs. 1 and 6.

As the rack bar 30 descends during the transmission of a signal, the inner end of the pawl 33 moves over the cam surface 40 at the lower end of the groove 39, moving the flat 30 face 36 of the pawl outward so that it is engaged by the flat upper end 37 of the pawl 27, as shown in Fig. 7, thereby resetting the mechanism for further operation.

I claim:—

35 1. A signal transmitter including a signal wheel, a make and break device operated thereby, a chain of gears operatively connected to the signal wheel, a pivoted segment, a weight suspended from the segment, a gear 40 carried by the segment, a rack bar operatively engaging the gear, a second rack bar, pawls upon the rack bars arranged to normally lock the bars together, an operating lever having a gearing portion engaging the second rack bar and means actuated by the upward movement of the rack bars for disengaging said pawls when the segment is raised to its highest point.

2. A signal transmitter including a signal 50 wheel, a make and break device operated thereby, a chain of gears operatively connected to the signal wheel, a pivoted segment, a weight suspended from the segment, a gear

carried by the segment, a rack bar operatively engaging the gear, a second rack bar, means 55 arranged to normally lock the bars together, an operating lever having a gearing portion engaging the second rack bar and means actuated by the upward movement of the rack bars for disengaging said locking means when the segment is raised to its highest point.

3. A signal transmitter including a signal wheel, a make and break device operated thereby, a chain of gears operatively connected to the signal wheel, a pivoted segment, 65 means connected to the segment for storing up energy to transmit a signal, a gear carried by the segment, a rack bar operatively engaging the gear a second rack bar, pawls upon the rack bars arranged to normally lock 70 the bars together, an operating lever having a gearing portion engaging the second rack bar and means actuated by the upward movement of the rack bars for disengaging said pawls when the segment is raised to its high- 75 est point.

4. A signal transmitter including a signal wheel, a make and break device operated thereby, a chain of gears operatively connected to the signal wheel, a pivoted segment, 80 means connected to the segment for storing up energy to transmit a signal, a gear carried by the segment, a rack bar operatively engaging the gear, a second rack bar, means arranged to normally lock the bars 85 together, an operating lever having a gearing portion engaging the second rack bar and means actuated by the upward movement of the rack bars for disengaging said locking means when the segment is raised to its high- 90 est point.

5. A signal transmitter including a signal wheel, a make and break device operated thereby, a chain of gears operatively connected to the signal wheel, a pivoted segment, 95 a weight suspended from the segment, an operating lever and winding means associated therewith for rocking the segment upward to raise the weight, and to operatively connect the segment to the chain of gears, and means 100 for automatically disconnecting the operating lever from the winding means when the lever is released without completely raising the weight or when the weight is completely raised even when the lever is not released.

RALPH W. CARNahan.
